UNITED STATES PATENT OFFICE.

ISIDORE BAROUH, OF PARIS, FRANCE.

DESIGN FOR A BOTTLE.

Application filed November 10, 1928. Serial No. 28,823. Term of patent 3½ years.

To all whom it may concern:

Be it known that I, ISIDORE BAROUH, a citizen of the Republic of Cuba, residing at Paris, Republic of France, have invented a new, original, and ornamental Design for a Bottle, of which the following is a specification, reference being had to the accompanying drawing, forming a part thereof.

In the drawing,
Fig. 1 is a front perspective view of my design, and
Fig. 2 is a side view thereof.

I claim:
The ornamental design for a bottle substantially as shown.

ISIDORE BAROUH.
